UNITED STATES PATENT OFFICE.

WILLIAM WIEDEMANN, OF LAWRENCE, KANSAS.

CURTAIN-FASTENER.

SPECIFICATION forming part of Letters Patent No. 347,543, dated August 17, 1886.

Application filed February 2, 1886. Serial No. 190,617. (No model.)

To all whom it may concern:

Be it known that I, WILLIAM WIEDEMANN, of Lawrence, in the county of Douglas and State of Kansas, have invented a new and Improved Curtain-Fastener, of which the following is a full, clear, and exact description.

This invention relates to an improved form of curtain - fastener which may be readily brought into engagement with the retaining-button, and which, when so engaged, will not be liable to accidental displacement; and to the end named the invention consists of certain details of construction and combinations of parts, to be hereinafter more fully explained, and specifically pointed out in the claims.

Reference is to be had to the accompanying drawings, forming a part of this specification, in which similar letters of reference indicate corresponding parts in all the figures.

Figure 1 is a view of a portion of a curtain provided with my improved form of fastener. Fig. 2 is a view of the under side of the fastener removed from the curtain. Fig. 3 is a view of the retaining-ring. Fig. 4 is a sectional view taken on line $\alpha\alpha$ of Fig. 1. Figs. 5, 6, 7, and 8 are detail views illustrating the construction of the jaws.

In the construction of such a fastener as is illustrated in the drawings above referred to, I provide an annular base-plate, A, provided with clamping-ears $a a$, and to this plate A, I pivotally connect two jaws, B and C, by means of a pivot-bolt, b. Each of the jaws B and C is provided with a semicircular central recess, c, and with manipulating-arms $d d$, formed with thumb-wings $e e$, and each of the jaws is also formed with a notch, f. At the point of pivotal connection with the plate A the jaw B is provided with a semicircular lug or projection, g; which lies flat upon the plate A, while the jaw C is formed with a projection, h, that is struck up so as to overlap the projection g, the pivot b being passed through apertures i, formed in said lugs or projections. The washer k is placed over the projection h, and above this washer and about the pivot b there is coiled a spring, l, the extending end of which project upward and bear against the inner faces of the thumb-wings $e e$, thus holding the jaws B and C in the position shown in Fig. 1, the

alignment of the parts being secured by means of a stop, n, formed on the plate A, and the ends of the jaws are held to the plate by overlapping ears o.

In applying such a fastener as has been described to a carriage or other form of curtain, the ears $a a$ are forced through the body of the curtain or passed through apertures formed therein, after which a retaining-ring, N, formed with apertures $p p$, made to register with the lugs, is placed in the position shown in Fig. 4, after which the ears a are turned down, as shown in said figure, to clamp the fastener to the curtain. The curtain is then cut away, as shown at m, Fig. 4, to permit a passage of the button, (shown in dotted lines at M,) the jaws B C being thrown apart by pressure applied to the thumb-wings $e e$ to permit the head of the button to pass between the jaws, so that when the pressure is released the jaws will close about the shank of the button, as indicated in Fig. 4.

Such a fastener as has been described will hold the curtain against displacement by the wind, and is easily manipulated in buttoning and unbuttoning the curtain.

I am aware that a curved spring-operated catch has been pivoted within a centrally-apertured hollow disk having a centrally-apertured rear face-plate; also, that two flat jaws have been pivoted at their adjacent faces to form a circular aperture to receive a knob; also, that the outer ring of a curtain-fastener has been provided with clinching-prongs that were passed through the curtains and bent around an inner ring, and I do not claim such, broadly, as of my invention.

Having thus fully described my invention, what I claim as new, and desire to secure by Letters Patent, is—

1. In a curtain-fastener, the combination, with an annular base-plate, of jaws B C, pivoted between their ends and having arms $d d$, formed with thumb-wings $e e$ on their outer edges, and recesses $c c$ in the inner adjacent edges of the jaws, and a spring, l, bearing at its ends on the wings $e e$, substantially as set forth.

2. In a curtain-fastener, the combination, with an annular base-plate provided with ears $a a$ and $o o$ and a stop, n, of jaws B C, formed

with arms *d d*, recesses *e e*, and notches *ff*, a spring, *l*, and retaining-plate *N*, substantially as described.

3. In a curtain-fastener, the combination, 5 with a base-plate formed with ears *aa* and *oo*, of jaws *B C*, formed, respectively, with lugs or projections *g* and *h*, and each jaw being formed

with an arm, *d*, a recess, *e*, and a notch, *f*, spring *l*, and retaining-plate *N*, substantially as described.

WILLIAM WIEDEMANN.
